United States Patent

Des. 237,658
Patented Nov. 18, 1975

237,658

SPOOL HOLDER

Stig Boman, Billdal, and Rolf Wallin, Floda, Sweden,
assignors to Molnlycke AB, Goteborg, Sweden

Filed May 14, 1973, Ser. No. 359,778

Claims priority, application Sweden Nov. 13, 1972

Term of patent 14 years

Int. Cl. D3—01

U.S. Cl. D3—19 D

FIG. 1

FIG. 3

FIG. 2

FIG. 1 is a side elevational view of a spool holder showing our new design, the side opposite being identical thereto;

FIG. 2 is a top plan view thereof; and

FIG. 3 is a side elevational view, the broken line showing of spools and thread being for purposes of illustration only.

We claim:

The ornamental design for a spool holder, as shown and described.
